W. D. BLACKMAN, OF DEFIANCE, OHIO.

Letters Patent No. 66,288, dated July 2, 1867.

PHOTOGRAPHIC COPYING-BOARD.

The Schedule referred to in these Letters Patent and making part of the same.

TO ALL WHOM IT MAY CONCERN:

Be it known that I, W. D. BLACKMAN, of Defiance, Defiance county, Ohio, have invented a new and improved Photographic Copying-Board; and I do hereby declare that the following is a full, clear, and exact description thereof, which will enable others skilled in the art to make and use the same, reference being had to the accompanying drawings forming part of this specification, in which—

Figure 1 represents a side elevation, partly in section, of my improved photographic plate-holder, the plane of section being indicated by the line $z z$, fig. 2.

Figure 2 is a front elevation, partly in section, of the same.

Figure 3 is a detail vertical sectional view of the same, the plane of section being indicated by the line $x x$, fig. 2.

Figure 4 is a horizontal sectional view of the same, the plane of section being indicated by the line $y y$, fig. 2.

Figure 5 is an inside view of one of the jaws for holding the picture.

Similar letters of reference indicate corresponding parts.

The object of this invention is to facilitate the copying of old pictures, such as photographs, ambrotypes, daguerreotypes, and others, by photographic process.

The invention consists in constructing and arranging an apparatus in which the aforesaid old pictures can be held; said apparatus being so constructed that pictures of different sizes can be firmly held therein, and so that the pictures in it can be moved to or from the camera to adjust the focus, and raised or lower to be centred.

A represents a horizontal board or platform, upon the front end of which the camera stands. In its rear end, b is arranged a slot, in which a block, B, slides, said block being provided with flanges $c c$, which overlap the edges of the slot, as shown in fig. 2. In the block B is arranged an upright sliding-post, C, which is provided with a ratchet-bar, d , on one side, into which a pinion, e , meshes. This pinion is mounted on a shaft, D, which extends through the whole length of that portion of the board A that is in front of the slats; the front end of the said shaft being provided with a crank or hand-wheel, f . By turning the said shaft D the post c can be raised or lowered at will in the block B. Another shaft E passes from the front part of the plate A into and through the block B, being provided with a screw-thread at its rear end, and passing through a nut, g , that is arranged in the said block, as is clearly shown in fig. 3. Thus by turning the shaft E the block B and its appendages can be brought nearer to or further from the camera. The pinion e must slide on the shaft D so that it can be carried along with the block B, that portion of the shaft D being squared for the purpose. To the upper end of the sliding upright post C is pivoted a disk, F, which has two ears $h h$, through which the pivoting pin i passes, as is clearly shown in fig. 2. In this disk are two slots, which are arranged on either side of the centre on the horizontal diameter, and as indicated in fig. 4; the said slot reaching almost from the centre to the rim, as shown. Through each one of the slots in the disk F passes a pin, j , which is squared in the slot, as shown in fig. 4. From the centre of the disk F projects towards the rear a fixed horizontal pin, k , upon which a revolving disk, G, is hung, in which eccentric slots are arranged, as is clearly shown in fig. 2. The pins j pass through these eccentric curvilinear slots, and are provided with heads on their front and rear ends. The front end of each pin j passes through an almost semicircular plate H, fig. 5, the cord or straight line of each plate H being vertical, as is indicated by dotted lines in fig. 2. By revolving the disk G around the pin R , the pins j are moved in the eccentric slots further from or nearer to the centre of the disk, and do thereby bring the plates H more or less apart so as to adapt the apparatus for holding larger or smaller pictures. On the inner side of each plate H is arranged a spring, l , which carries a straight vertical rod, m , near to and parallel with the straight edge of the said plate H, as shown in fig. 5. These rods m serve as rests or frames for the picture, and are, by turning the disk G, brought close to the edge of the picture. I is a knob, having a tubular extension, n , which fits the centre of the disk G, and surrounds the central spindle R of the disk F. On the front end of the tube n are teeth making it appear like a clutch, and corresponding teeth are formed on the inside of the disk F, as shown in fig. 4. By turning the knob I the plate G can be drawn away from the disk F, and the plates H will thereby be clamped against the disk F, which will be understood from fig. 4; the knob I being turned so that the projecting parts of n are over the higher parts of the clutch on F. Thereby the picture will be firmly clamped between the plates H and the disk F.

By means of the shaft D the picture can be raised and lowered and centred; and by the shaft E it can be moved nearer to or further from the camera, and its focus regulated.

Having thus described my invention, what I claim as new, and desire to secure by Letters Patent, is—

1. A photographic copying-board, made and operating substantially as and for the purposes herein specified and described.

2. The device for centring the picture that is held on the plate F, said device consisting of the ratchet-bar d C, pinion e, and shaft D, all made and operating substantially as herein specified and described.

3. The device for adjusting the focus of the picture that is held on the plate F, said device consisting of the sliding-block B, nut g, and screw-shaft E, all made and operating substantially as and for the purpose herein specified and described.

4. The device for increasing the size of the frame for holding the picture to be photographed, said device consisting of the stationary disk F, revolving disk G, pins j; plates H, and spring-bars m, all made and operating substantially as and for the purpose herein specified and described.

5. The device for clamping the picture, consisting of the revolving clutch I, in combination with the stationary clutch F, disk G, pins j, and plates H, all made and operating substantially as described.

The above specification of my invention signed by me this 27th day of March, 1867.

W. D. BLACKMAN.
